UNITED STATES PATENT OFFICE.

OSCAR A. WADE, OF AVON, MASSACHUSETTS, ASSIGNOR OF ONE-HALF TO
GODFREY KNIGHT, OF AVON, MASSACHUSETTS.

PICTURE-HANGER.

SPECIFICATION forming part of Letters Patent No. 740,493, dated October 6, 1903.

Application filed January 14, 1903. Serial No. 138,972. (No model.)

To all whom it may concern:

Be it known that I, OSCAR A. WADE, of Avon, in the county of Norfolk and State of Massachusetts, have invented certain new and useful Improvements in Picture-Hangers, of which the following is a specification.

This invention has for its object to provide a picture-hanger adapted to project upwardly by reason of its own inherent stiffness from a picture-frame to which it is attached, so that the picture may be hung and removed by a person grasping only the frame.

The invention also has for its object to provide a picture-hanger adapted to insure a horizontal position of the picture-frame hung thereby and also adapted to be conveniently adjusted to vary the height of the picture.

The invention consists in the improvements which I will now proceed to describe and claim.

Of the accompanying drawings, forming a part of this specification, Figure 1 represents a front view of a picture-frame suspended by a hanger embodying my invention. Fig. 2 represents an enlarged front view of the hanger, parts thereof being broken away. Fig. 3 represents an edge view showing the parts represented in Fig. 2. Fig. 4 represents an enlarged section on line 4-4 of Fig. 2. Fig. 5 represents an enlarged section on line 5-5 of Fig. 2. Fig. 6 represents an enlarged section on line 6-6 of Fig. 2. Fig. 7 represents an enlarged section on line 7-7 of Fig. 2.

The same reference characters indicate the same parts in all the figures.

In the drawings, *a* represents a hook adapted to engage an ordinary molding-strip *b*, attached to a wall, the hook being preferably made of sheet metal and having sufficient width to have a broad bearing on the molding, whereby the hook will be prevented from tipping to either side. To the hook *a* at two independent points are connected two suspension-rods, which are adapted to diverge from the hook at different angles and are formed at their lower ends to receive screw-eyes or other attaching devices, whereby the suspension-rods may be attached to a picture-frame *c*. Different angles of divergence are

obtainable, because the suspension-rods are pivotally connected to the hook and may spread more or less, according to the width of the picture to which they are attached. Moreover, since the said rods are independently adjustable in length, as hereinafter described, they will depend at different angles relatively to the vertical line of the hook if one be set shorter than the other. The said suspension-rods are constructed in the present embodiment of my invention as will now be described. Each rod is composed of an upper section *d* and a lower section *e*. The upper section *d* is preferably composed of a length of wire formed at its upper end into an eye *d'*, which is secured to the lower portion of the hook *a* by means of a tubular or other rivet *d''*, the two rivets *d''* being side by side. The lower end of the section *d* is bent to form a hook *d'''*.

The section *e* is preferably composed of a strip of flatsheet metal bent at its upper end to form an ear *e'*, in which is an orifice *e''*, through which one of the wire sections *d* passes. Below the ear *e'* are formed orifices *e''' e''''*, of which there may be any desired number, two being here shown, either of said orifices being adapted to receive a hook *d'''*. Provision is thus made for adjusting the length of the suspension-rods. The section *e* is preferably composed of an upper member 8 and a lower member 9, the two members being jointed together by means of a tubular rivet or eyelet 10, which permits the lower member 9 to be swung inwardly from the general line of the rod of which it forms a part, as shown in dotted lines in Fig. 1. The tubular rivet 10 is adapted to receive a screw or other attaching device used to connect the suspension-rod of which it forms a part to the picture-frame. The lower end of the member 9 is provided with an orifice 12, also adapted to receive a screw or other attaching device.

It will be seen that the hanger above described, comprising two practically independent suspension-rods adapted to diverge at different angles from the hook *a*, enables the picture to be suspended from a single hook without any liability of being tipped out of

a horizontal position. This is due to the fact that the hook is wide to have a broad bearing on the molding, so that the hook itself will not swing, and the two suspension-rods being independently secured to the hook prevent the picture from swinging relatively to the hook. It will also be seen that provision is made for adjusting the height of the picture, first, by shifting the hooks d^3 from one set of orifices e^3 to another, and, secondly, by inserting the attaching-screws either through the tubular eyelets 10 or through the orifices 12. When the attaching-screws are inserted in the tubular eyelets 10, the lower members 9 are swung inwardly, as shown in Fig. 1, said members being then inoperative and concealed behind the picture. The lower portions of the upper members are preferably bent, as indicated at 13, the portions below the bend standing at an angle to the portions above. The lower portions of the rods are thus enabled to conform to the slant of the picture-frame.

I do not limit myself to the exact details of construction, as the specific features thereof may be variously modified within the terms of the claims hereto appended.

When a picture-frame of medium size is employed, the upper end of the frame usually conceals the portions $e e$, as indicated by dotted lines in Fig. 1, only the wire portions $d d$ and the hook a being visible.

It will be seen that the suspension-rods are relatively stiff or self-supporting when attached to the frame, so that they project normally above the frame and support the hook in an elevated position, thus enabling the picture to be conveniently hung, the operator holding only the frame while hanging the picture. The stiffness of the suspension-rods enables a person to hang or remove a picture in most cases while standing on the floor and without the necessity of mounting a chair or step-ladder, and owing to the independent connection of the two rods with the hook said hook cannot tip or swing laterally relatively to the rods, and therefore the hook will stand upright and in position to be caught on the molding.

The orifices 12 in the lower portions of the members 9 may be of elongated form. If elongated, as indicated in Fig. 2, the slots are adapted to permit the passage of the ring portions of screw-eyes, which are commonly inserted in the back of the frame. Such eyes may be given a quarter-turn after insertion in said slots, so that they will extend cross-wise of the slots, thus locking the members 9 to the frame.

The outer portions 14 of the hooks d^3 are curved outwardly from the sections d , on which they are formed, to facilitate their insertion in the orifices e^3 . When the hooks are inserted, the spring of the sections d , together with the confinement of said sections

by the ears e' , cause the bends 14 of the hooks to project through the orifices e^3 and bear against the walls of said orifices in such manner as to prevent endwise movement of the sections d . Hence said sections cannot be disengaged and moved endwise until they are sprung from their normal position sufficiently to permit the removal of the hooks from the orifices e^3 .

I claim—

1. A picture-hanger comprising a hook having a wide bearing adapted to engage a molding-strip, and a plurality of suspension-rods pivotally connected to the hook at different points and adapted to diverge therefrom at different angles, said rods being attachable at their lower ends to a picture-frame.

2. A picture-hanger comprising a hook having a wide bearing adapted to engage a molding-strip, and a pair of suspension-rods jointed independently to said hook and adapted to diverge therefrom at different angles, said rods having orifices at their lower ends to receive attaching devices.

3. A picture-hanger comprising a hook having a wide bearing adapted to engage a molding-strip, and a pair of suspension-rods pivoted to the hook at different points and adapted to diverge therefrom at different angles, each rod being composed of sections having provisions for adjustment of the length of the rods, the lower portions of the rods having orifices to receive attaching devices.

4. A picture-hanger comprising a hook having a wide bearing adapted to engage a molding-strip, and a pair of suspension-rods pivotally connected to the hook at different points and adapted to diverge therefrom at different angles, each rod having an upper section of wire hooked at its lower end and a sliding lower section perforated to engage and slide on the wire section and provided with an orifice to receive an attaching device.

5. A picture-hanger comprising a hook adapted to engage a molding-strip, and a pair of suspension-rods connected to the hook and adapted to diverge therefrom at different angles, each rod having an upper section of wire hooked at its lower end, and a lower section composed of two members jointed together by a tubular pivot adapted to receive an attaching device, the upper member being perforated to engage the wire section, while the lower member is adapted to swing on the tubular pivot and is provided with an orifice in its outer end.

6. A picture-hanger comprising a hook adapted to engage a molding-strip, and a pair of suspension-rods connected to the hook and adapted to diverge therefrom at different angles, each rod having an upper section of wire hooked at its lower end, and a lower section composed of two members jointed together by a tubular pivot adapted to receive an attaching-screw, the upper member having a perforation.

rated ear at its upper end and a plurality of orifices below said ear, the wire section passing through said ear, while its hook enters one of said orifices, the lower member having a 5 screw-receiving orifice at its lower end and being bent so that its main portion stands at an angle to the upper member.

In testimony whereof I have affixed my signature in presence of two witnesses.

OSCAR A. WADE.
